CLAIM

The ornamental design for a building, as shown and described.

DESCRIPTION

FIG. 1 is a perspective view of a building showing my new design;

FIG. 2 is a front view of the building;

FIG. 3 is an enlarged view of FIG. 2 showing an entry screen;

FIG. 4 is an enlarged fragment of the entry screen of FIG. 3;

FIG. 5 is a right side view of the entry screen of FIG. 3;

FIG. 6 is a rear view of the building;

FIG. 7 is a left side view of the building; and,

FIG. 8 is a right side view of the building.

The curved lines in FIGS. 4 and 5 represent a reduction in space between the sections.

The broken line showing of a surrounding building, trees, people, street, and automobile in FIG. 1, and the broken line showing of parts of the building in FIGS. 2-8, is included for the purpose of showing the environment of the building and forms no part of the claimed design.
